(57) **CLAIM**

The ornamental design for a collapsible metal detector, as shown and described.

DESCRIPTION

FIG. 1 is an upper perspective view of a collapsible metal detector, showing our new design in a collapsed condition; FIG. 2 is a lower perspective view thereof in the collapsed condition;

FIG. 3 is a front view thereof in the collapsed condition; FIG. 4 is a top view thereof in the collapsed condition; FIG. 5 is a right side view thereof in the collapsed condition; FIG. 6 is a left side view thereof in the collapsed condition; FIG. 7 is a bottom view thereof in the collapsed condition; FIG. 8 is a rear view thereof in the collapsed condition; FIG. 9 is an upper perspective view thereof in an extended condition;

FIG. 10 is a lower perspective view thereof in the extended condition;

FIG. 11 is a top view thereof in the extended condition;

FIG. 12 is a right side view thereof in the extended condition;

FIG. 13 is a rear view thereof in the extended condition;

FIG. 14 is a left side view thereof in the extended condition;

FIG. 15 is a bottom view thereof in the extended condition; and,

FIG. 16 is a front view thereof in the extended condition.
